UNITED STATES PATENT OFFICE

WILLIAM D. LEWIS, OF PLYMOUTH, PENNSYLVANIA.

TROLLEY-GUARD.

No. 902,420.

Specification of Letters Patent. Patented Oct. 27, 1893.

Application filed April 11, 1893. Serial No. 226,462.

To all whom it may concern:

Be it known that I, WILLIAM D. LEWIS, a citizen of the United States, residing at Plymouth, in the county of Luzerne and State of Pennsylvania, have invented new and useful Improvements in Trolley-Guards, of which the following is a specification.

This invention relates to trolley guards and the object thereof is to provide an improved guard for trolley wheels in which the movement necessary to pass obstructions is reduced to a minimum as well as being quick and even and furthermore acting as a medium to maintain the conductor upon the trolley wheel when passing an obstruction, crossing railroad tracks, rounding curves and when switching.

A further object of the invention is to provide a guard for trolley wheels which is capable of adjustment to provide for variations in the angular position of the trolley pole with respect to the car as well as furthermore providing a trolley guard which is effective and durable in use, compact and simple in construction, and one which may be quickly applied to a trolley of the usual construction as well as acting as a guard to prevent injury to the trolley wheel when meeting with an obstruction.

With the foregoing and other objects in view, the invention consists of the novel construction, combination and arrangement of parts hereinafter more specifically described and illustrated in the accompanying drawings wherein is shown the preferred embodiment of the invention, but it is to be understood that changes, variations and modifications can be resorted to which come within the scope of the claims hereunto appended.

In the drawings wherein like reference characters denote corresponding parts throughout the several views:—Fig. 1 is a side elevation, showing the adaptation of a trolley guard in accordance with this invention in connection with the trolley. Fig. 2 is a rear elevation. Fig. 3 is a disassembled view of the elements constituting the adjusting and supporting means for the guard frame, and Fig. 4 is a perspective view of the guard frame with the combined retaining and cushioning spring removed.

Referring to the drawings in detail, 1 denotes a trolley pole which is broken away and is provided at one end with the usual harp 2 and in the harp 2 is journaled the

wheel 3 through the medium of a shaft 4, the latter projecting from each side of the harp 2. Upon the projecting ends of the shaft 4 is mounted a guard frame composed of a pair of vertically extending members 5, 6 connected together at their lower end by a bridge piece 7 from which depends a cylindrical arm 8. Each of the members 5, 6 at their upper end is bent inwardly as at 9 and 10, the upper end of the said inwardly extending portion 9 terminates in a segment-shaped retainer 11 arranged in close proximity to the shaft 4. Below the turned portion 9 of each of the vertical members of the guard frame is a vertically extending elongated slot 12 by which is provided, whereby the said guard frame can be mounted upon the projecting ends of the shaft 4. The latter at one end is headed or enlarged as at 13 and at its other end is provided with a cotter pin 14 and by such arrangement the guard frame is maintained upon the shaft 4.

The guard frame is supported through the medium of a swivelly mounted ring 15 through which extends the lower end of the arm 8 and against which abuts a combined retaining and cushioning spring 16, the latter surrounding the arm 8 and also abutting against the bridge 7. The ring 15 is formed with a pair of lugs 17 which are mounted in these at 18 provided with a yoke 19 formed integral with one end of an adjustable slotted arm 20. The slot in the arm 20, as indicated by the reference character 21 is somewhat elongated and extends longitudinally of the said arm 20. The latter is mounted in a channeled supporting arm 22 provided with a series of openings 23 through which is adapted to extend the adjusting screw 24 for connecting the arm 20 to the supporting arm 22. The screw 24 extends through the slot 21 as clearly shown in Fig. 1. The supporting arm 22 terminates in one section of a clamp 25 which is adapted to abut against the trolley pole 1. The other section of the clamp is indicated by the reference character 26 and the said sections 23, 24 are formed with laterally extending open-tured lugs 27 through which extend clevising screws 28 for fixedly securing the clamp to the trolley pole 1. The supporting arm 22 is angularly disposed with respect to the section 23 of the clamp and the arm 20 is angularly disposed with respect to the yoke 19. The said arms 20 and 22 extend in the same direction. Owing to the adjustable construc-

tion between the arms 18 and 20, a means is provided whereby the guard frame can be maintained in a vertical position, irrespective of the angle in which the trolley pole 5 extends and this provision is also obtained owing to the manner in which the guard frame is connected with the arm 18, that is to say through the medium of a swivelly mounted ring 13. If the connection were 10 fixed between the guard frame and the arm 18, it is evident that the guard frame could not be maintained in a vertical position, irrespective of the varying angular positions of the trolley pole.

15 It is thought that the operation of the guard can be thoroughly understood owing to its simplicity, but it will be stated that when the enlarged segment-shaped portions 9 meet with an obstruction or a switch on 20 the wire, they will gradually cause, owing to their shape, the lowering of the guard frame and readily pass the obstruction, and after the obstruction is passed owing to the expanding of the spring 14 the guard frame 25 will be returned to its normal position which is as clearly shown in Figs. 1 and 2.

What I claim is:—

1. A trolley guard comprising a guard frame provided at one end with a segment-shaped enlargement, an adjustable supporting means for said frame, and means constituting a swiveled connection between the frame and the supporting means.
2. A trolley guard comprising a guard frame provided at one end with a segment-shaped enlargement, an adjustable supporting means for said frame, means constituting a swiveled connection between the frame and the supporting means, and a combined 35 retaining and cushioning spring carried by the frame and abutting against the swiveled connection.

3. A trolley guard comprising a guard frame mounted upon the pivot of the trolley wheel and having its upper end projecting 45 above the wheel, an adjustable supporting means for said frame, and a swiveled connection between the supporting means and the frame.

4. A trolley guard comprising a guard 50 frame mounted upon the pivot of the trolley wheel and having its upper end projecting above the wheel, an adjustable supporting means for said frame, a swiveled connection between the supporting means and the frame, 55 and a combined retaining and cushioning spring carried by the frame and abutting against said swiveled connection.

5. A trolley guard comprising a vertically shiftable slotted guard frame connected 60 with the trolley harp and extending above the trolley wheel, an adjustable supporting means for said frame, said supporting means fixed to the trolley pole, and a swiveled connection between the guard frame and said 65 supporting means.

6. A trolley guard comprising a vertically shiftable slotted guard frame connected with the trolley harp and extending above the trolley wheel, an adjustable supporting 70 means for said frame, said supporting means fixed to the trolley pole, a swiveled connection between the guard frame and said supporting means, said frame provided with a depending arm, and a spring surrounding 75 said arm and abutting against the frame and said swiveled connection.

In testimony whereof I have hereunto set my hand in presence of two subscribing witnesses.

WILLIAM D. LEWIS.
